UNITED STATES PATENT OFFICE.

GEORGE L. TURNER, OF TAUNTON, MASSACHUSETTS, ASSIGNOR TO REED & BARTON CORPORATION, OF TAUNTON, MASSACHUSETTS.

DESIGN FOR A SPOON OR SIMILAR ARTICLE.

Application filed April 14, 1924. Serial No. 9,278. Term of patent 7 years.

To all whom it may concern:

Be it known that I, GEORGE L. TURNER, of Taunton, in the county of Bristol and State of Massachusetts, have invented a new, original, and ornamental Design for a Spoon or Similar Article, of which the following is a specification, reference being made to the accompanying drawing, forming part thereof.

The figure is a plan view of a spoon showing my new design.

I claim—

The ornamental design for a spoon or similar article as shown.

GEORGE L. TURNER.
